UNITED STATES PATENT OFFICE.

LEVI HAYNE, OF SCHENECTADY, NEW YORK, ASSIGNOR TO PIKE MANUFACTURING COMPANY, OF PIKE, NEW HAMPSHIRE, A CORPORATION OF NEW HAMPSHIRE.

PENCIL-SHARPENER.

1,008,716.

Specification of Letters Patent. Patented Nov. 14, 1911.

Application filed December 15, 1910. Serial No. 597,458.

To all whom it may concern:

Be it known that I, LEVI HAYNE, a citizen of the United States, and a resident of Schenectady, county of Schenectady, and 5 State of New York, have invented certain new and useful Improvements in Pencil-Sharpener, of which the following is a full, clear, and exact description.

This invention relates more particularly 10 to a pencil sharpener in which the sharpening element is in the form of a disk.

The primary object of the invention is to provide a simple and efficient device in which the sharpening element is so made 15 that it will operate to grind or sharpen a pencil or other object from two points adjacent to each other so that a very fine point may be obtained without the liability of breaking the lead, as is very often the case 20 with devices of this kind as ordinarily constructed.

Another object of the invention is to provide a sharpening element which may be easily made and which may be applied to 25 various forms of devices.

A further object of the invention is to provide a metallic sharpening element in which there are two sharpening fields or zones arranged to operate upon the object 30 from two directions and which sharpening fields are located upon the face of a disk.

With these and other objects in view, the invention will be hereinafter more particularly described with reference to the accompanying 35 drawings, which form a part of this specification, and will then be pointed out in the claims at the end of the description.

In the drawings, Figure 1 is a plan view, 40 partly in elevation and partly broken away, of one form of device embodying my invention, showing how the sharpening element may be manually operated. Fig. 2 is an enlarged face view of the disk, showing a pencil held in position to be sharpened. Fig. 3 is an enlarged transverse section, 45 taken on the line III—III of Fig. 2; and Fig. 4 is an enlarged fragmentary section, taken on the line IV—IV of Fig. 2.

The casing 10 may have suitable means

to permit it to be held to a support, and in the casing is a gear 11 which is held to a shaft 12, and on this shaft 12 is a handle 13 by which the shaft 12 may be rotated. A pinion 14 is secured to the shaft 15 and this 55 pinion is in mesh with the large gear 13 so that when the latter is rotated through the handle 13 the shaft will be rapidly rotated owing to the difference in the sizes of the pinion and gear. The shaft 15 like the shaft 60 12 may be journaled in bosses on the casing 10 and held to one end of a shaft 15 is a sharpening element 16. This disk 16 may be held to the shaft in any desired way, as by a collar 17 and a nut 18 arranged on the 65 end of the shaft 15 so as to clamp the element 16 to the collar 17 to rotate with the shaft 15.

The pencil 19 may be held in a holder or device 20 between two members 21 and 22 70 forming an opening through which the body of the pencil may pass and said holder may be suitably arranged to hold the pencil in proper position with respect to the element 16. The pencil holder or support 20 75 may be in the form of a bracket having an arm 23, one end of which is angularly formed at 24, and clamping this angularly formed end to an ear or lug 25 is a bolt 26, whereby on releasing the bolt the position 80 of the bracket 20 may be changed as well as detached if desired from the casing 10. The parts so far described may be of the usual or of any preferred construction except so far as the element 16 is concerned. 85

To prevent the pencil from being broken while sharpening the same, and at the same time secure effective means for this purpose, I provide on either or both faces of the element 16 two grinding or sharpening surfaces 27 and 28. As shown the element 16 is in the form of a disk and has two concentric circular surfaces, and these grinding surfaces are on one face only thereof, that is the outer face of the disk. The grinding 95 surface 29 comprises a plurality of grinding teeth, blades or parts 30, while the grinding surface 28 has a plurality of teeth or parts 31. The teeth 30 of the grinding surface or zone 27 are radially arranged and 100

may be of any desired number and of any desired length and located within the grinding surface or zone 28. The teeth or grinding parts 31 of the zone or grinding surface 5 28 are substantially tangentially arranged with respect to the teeth or grinding parts 30 of the grinding surface 27, and the pencil or object to be sharpened is so held with respect to the face of the disk that the teeth 10 31 will cut or sharpen the pencil from the body thereof toward the point or lead, while the teeth or grinding parts 30 will grind or sharpen the inner point or part of the pencil from the extreme point toward 15 the wood. This has the effect of causing the pencil to be sharpened at two distinct parts and toward each other one from the body of the wood outwardly toward the point and the other from the point 20 toward the body of the pencil, by which means the lead of the pencil is less likely to be broken and the point may be sharpened to any desired extent.

It will be understood that the grinding 25 element may be variously shaped, and that the teeth while shown as cut from a metallic disk-like object and on one side thereof, may have teeth similarly formed on the opposite face, as for example the face 32 of the disk, 30 so that when one face of the disk has lost its cutting or sharpening surface, it may be reversed and the other face used.

From the foregoing, it will be seen that 35 simple and efficient means is provided whereby a rotary sharpening element may have two grinding surfaces on the same face coöperating with each other to grind or sharpen a pencil or other object in two directions to adapt the same to provide a sharp 40 point; that simple means is provided for operating the grinding element; that said grinding element may be of metal with cutting surfaces on either or both faces thereof; and that said element is so constructed 45 that it may be readily made and at the same time provide an element which is very effective in use.

Having thus described my invention, I 50 claim as new and desire to secure by Letters Patent:—

1. In a sharpening device, a frame and a disk rotatably mounted on the frame, the disk being provided at the central portion of one face with cutting teeth extending in 55 a substantially radial direction and terminating in a circle concentric with the axis of the disk, said face of the disk also having cutting teeth extending from said circle to its edge in a direction tangential to said circle.

2. In a sharpening device the combination 60 of a frame, a disk rotatably mounted on the frame, the disk being provided at the central portion of one face with cutting teeth extending in a substantially radial direc-

tion and terminating in a circle concentric with the axis of the disk, said face of the disk also having cutting teeth extending from said circle to its edge in a direction tangential to said circle, and a holder arranged to support a pencil to have its extremity engaged by the radial teeth, and the portion beyond the extremity engaged by the tangential teeth. 70

3. In a sharpening device, the combination 75 of a frame, a disk rotatably mounted on the frame, the disk being provided at the central portion of one face with cutting teeth extending in a substantially radial direction and terminating in a circle 80 concentric with the axis of the disk, said face of the disk also having cutting teeth extending from said circle to its edge in a direction tangential to said circle, the said tangential teeth having their cutting edges 85 facing inwardly, and the radial teeth having their cutting edges extending in the same direction as the other teeth, whereby on rotation of the disk in a direction the same as that in which the tangential teeth extend 90 such teeth will cut by an inward movement while the other teeth will cut by a movement in the opposite direction.

4. In a sharpening device the combination 95 of a frame, a disk rotatably mounted on the frame, the disk being provided at the central portion of one face with cutting teeth extending in a substantially radial direction and terminating in a circle concentric with the axis of the disk, said face 100 of the disk also having cutting teeth extending from said circle to its edge in a direction tangential to said circle, the said tangential teeth having their cutting edges facing inwardly, and the radial teeth having their cutting edges extending in the same direction 105 as the other teeth, whereby on rotation of the disk in a direction the same as that in which the tangential teeth extend such teeth will cut by an inward movement while 110 the other teeth will cut by a movement in the opposite direction, and a holder arranged to support a pencil to have its extremity engaged by the radial teeth, and the portion beyond the extremity engaged by 115 the outer teeth.

5. In a sharpening device, a cutting element provided with two cutting portions provided with teeth, the outer extremities of the teeth of one cutting portion terminating 120 in a circle, the teeth of the other portion extending tangentially to the circle formed by the teeth of the first mentioned portion

6. In a sharpening device, a cutting element provided with two cutting portions 125 provided with teeth, the outer extremities of the teeth of one cutting portion terminating in a circle, the teeth of the other portion extending tangentially to the circle formed by the teeth of the first mentioned 130 portion

portion, and a holder arranged to support a pencil to have its extremity engaged by one set of teeth and the portion beyond the extremity engaged by the other or tangen-
5 tially arranged set of teeth.

7. In a sharpening device, a cutting element provided with two cutting portions, the teeth of one cutting portion extending in a radial direction, and the teeth of the

other portion extending at an angle to said 10 teeth

This specification signed and witnessed this 14th day of December A. D. 1910.
